(57) **CLAIM**

The ornamental design for a food thermometer set, as shown and described.

DESCRIPTION

FIG. 1 is a first perspective view of a first element of a food thermometer set showing our new design;

FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first element thereof;

FIG. 8 is a bottom view of the first element thereof;

FIG. 9 is a first perspective view of a second element of a food thermometer set showing our new design;

FIG. 10 is a second perspective view of the second element thereof;

FIG. 11 is a front view of the second element thereof;

FIG. 12 is a back view of the second element thereof;

FIG. 13 is a left side view of the second element thereof;

FIG. 14 is a right side view of the second element thereof;

FIG. 15 is a top view of the second element thereof;

FIG. 16 is a bottom view of the second element thereof;

FIG. 17 is a combination view of the first element and the

second element of the food thermometer set thereof; and,

FIG. 18 is an exploded view of the food thermometer set thereof.

The broken lines shown in the drawings depict portions of the food thermometer set that form no part of the claimed design.

1 Claim, 18 Drawing Sheets
